J. RITTER, JR.

GARMENT RETAINER

Filed June 1, 1926

UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

GARMENT RETAINER.

Application filed June 1, 1926. Serial No. 113,108.

This invention relates to improvements in garment retainers, more particularly adapted for use in wardrobe trunks.

Trunks of the wardrobe type are usually provided with wardrobe hangers, and the garments draped thereon hang downwardly and are engaged medially of their length by a retainer for maintaining the garments in place during transportation.

It is one of the objects of the present invention to provide an improved form of garment retainer having means for positively maintaining the retainer in adjusted position and for relieving the locking bolts of the strain of the load.

A further object of the invention is to provide a garment retainer having its garment engaging face formed of a yielding material to eliminate injury to the garments.

A further object of the invention is to provide a garment retainer which may be easily adjusted to various positions of use or removed from the trunk when desired.

A further object of the invention is to provide a garment retainer which is of simple construction, is strong and durable and is well adapted for the purpose described.

With the above and other objects in view, the invention consists of the improved garment retainer and its parts and combinations as set forth in the claims, and all equivalents thereof.

In the accompanying drawing in which the same reference characters indicate the same parts in all of the views:

Fig. 1 is a transverse sectional view of the wardrobe section of a wardrobe trunk provided with the improved garment retainer;

Fig. 2 is a vertical sectional view taken on line 2—2 of Fig. 1; and

Fig. 3 is a sectional detail view taken on line 3—3 of Fig. 1.

Referring to the drawing, the numeral 5 indicates the wardrobe section of a wardrobe trunk and 6 the open front portion thereof. Guide members 7 mounted on the inner opposite sides of the trunk section and extending from the front to the rear portions of said section are spaced from the side walls by the offset end portions 7' of the guide and secured thereto by rivets or screws 8. The guide members are provided with bolt openings 9 and vertically extending notches or recesses 10 in their upper edges between the bolt openings. The re-

tainer bar 11 is adapted to extend between the guide members 7 and is provided at its opposite ends with extension members 12 of angular form which rest in the notches 10 of the guides to take the outward strain caused by engagement with the garment held in place.

The end portions 13 of the extensions are angled rearwardly and are provided with bolt openings 14 which register with the bolt openings 9 adjacent the notches engaged by the extension members 12. Bolt casings 15 clamped around the end portions of the retainer bar are provided with slidable bolts 16 having springs 17 for yieldingly holding the bolts in a locking position. The said bolts are of sufficient length to extend through the guide members and also through the angular end portions 13 of the extensions 12, as clearly shown in Figs. 1 and 3. The inner side of the retainer bar is provided with a cushion member 18 which yieldingly engages the garments.

When the bolts are in locking engagement with the guide members, the extensions will be held in the notches and any outward strain on the retainer bar will be transmitted directly to the extension member 12 and thus relieve the bolts of the direct strain. In adjusting, it is only necessary to release the bolts from the guide members and then move the retainer to the position desired and then release the bolts to lock the parts together.

From the foregoing description, it will be seen that the garment retainer is of very simple construction and is well adapted for the purpose described.

What I claim as my invention is:

1. The combination with a wardrobe trunk section, of a garment retainer therefor, comprising guide members connected to the opposite inner sides of said trunk section and having bolt openings and upper edge recesses between the openings, a retainer bar positioned between the guide members, extension members mounted on the opposite end portions of the bar and having portions which extend through some of the recesses to take the outward strain of the bar, and bolts mounted on the opposite end portions of the retainer bar and lockingly entering the bolt openings, and engaging the extension members.

2. The combination with a wardrobe

- trunk section, of a garment retainer there-
for, comprising guide members connected to
the opposite inner sides of said trunk sec-
tion and having bolt openings and upper
edge recesses between the openings, a re-
tainer bar positioned between the guide
members, extension members mounted on the
opposite end portions of the bar and hav-
ing portions which extend through some of
the recesses to take the outward strain of the
bar, and also having angular portions pro-
vided with bolt openings, and bolts mounted
on the opposite end portions of the retainer
bar and extending through the bolt open-
ings of the guide members and the extension
members.
3. The combination with a wardrobe
trunk section, of a garment retainer there-
for, comprising guide members having off-
set portions connected to the opposite inner
sides of the trunk section, said guide mem-
bers having lines of bolt openings and upper
edge vertically extending recesses be-
tween said openings, a retainer bar posi-
tioned between the guide members, extension
members mounted on the opposite end por-
tions of the bar and extending through
some of the recesses to take the outward strain of the
bar, said extensions also hav-
ing right angular end parts formed with 30
bolt openings which will register with any
of the bolt openings of the guide members,
and spring actuated bolts mounted on oppo-
site end portions of the retainer bar and
lockingly entering some of the openings of 35
the guide members and the openings of the
extension members.
4. A retainer bar construction, compris-
ing a pair of spaced guide members having
bolt openings and edge recesses, a retainer
bar member positioned between the guide
members, extension members mounted on the
opposite outer end portions of the bar and
extending through some of the recesses and
having angular end portions provided with 40
bolt openings, and bolts mounted on the op-
posite end portions of the retainer bar and
extending through some of the guide mem-
ber bolt openings and also through the bolt
openings of the extension members. 45
50

In testimony whereof, I affix my signature.

JULIUS RITTER, Jr.
